UNITED STATES PATENT OFFICE.

JOHN McE. AMES, OF NEW BRIGHTON, NEW YORK.

BODY-BOLSTER FOR RAILWAY-CARS.

No. 833,147.

Specification of Letters Patent.

Patented Oct. 16, 1906.

Application filed January 6, 1906. Serial No. 294,835.

To all whom it may concern:

Be it known that I, JOHN McE. AMES, a citizen of the United States, and a resident of New Brighton, in the county of Richmond and State of New York, have invented certain new and useful Improvements in Body-Bolsters for Railway-Cars, of which the following is a specification.

The invention relates to improvements in body-bolsters for railway-cars; and it consists in the novel features and construction hereinafter described, and particularly pointed out in the claims.

The object of the invention is to provide a bolster composed of separable parts capable of convenient removal from and application to the car-body without disturbing the structural features of the latter.

The invention will be fully understood from the detailed description hereinafter presented, reference being had to the accompanying drawings, in which—

Figure 1 is a top view of one-half of a body-bolster constructed in accordance with and embodying my invention. Fig. 2 is a side elevation of same, the structural features of the car present being shown in transverse section. Fig. 3 is a detached view of one end of the bolster. Fig. 4 is a detached top view of a top plate for connecting the main members of the bolster together. Fig. 5 is a transverse section of same on the dotted line 5 5 of Fig. 4. Fig. 6 is a side elevation of the complete bolster, the structural features of the car present being shown in transverse section. Fig. 7 is a detached side view of one of the end members of the bolster. Fig. 8 is an enlarged detached side view of a center plate and center-sill filler forming a part or member of the bolster. Fig. 9 is a bottom view of same. Fig. 10 is a vertical transverse section of same on the dotted line 10 10 of Fig. 9; and Figs. 11, 12, and 13 are perspective views of a portion of the middle part of the bolster and illustrate several modifications which may be made in the construction thereof, and particularly as to the manner of connecting the top or tie plate with the main members of the bolster.

In the drawings, 10 designates the two main members of the bolster; 11, the top connecting-plate; 12, a frame affording the center plate and center-sill filler, and 13 fillers interposed between the center sills 14 and adjacent ends of the bolster members 10.

The structural features of the car shown

are the center sills 14, the plate 15 upon said sills, and the side sills or members 16, and these specified features are usual in car constructions and require no special description. 60

The main members 10, which are of cast metal, correspond with each other in form and construction and each comprises a central vertical web 17, oppositely-extending top flanges 18, oppositely-extending bottom 65 flanges 19, oppositely-extending outer-end flanges 20, and oppositely-extending inner-end flanges 21.

The top plate 11 connects or ties together the inner ends of the bolster members 10, and said plate 11 is preferably of cast metal and formed on its top with a longitudinal broad rib 22 and depending brackets 23 to receive the car-timbers. The ends of the plate 11 may be secured by rivets 24 to the top flanges 75 of the bolster members 10, as shown in Fig. 1, said flanges broadening out adjacent to their inner ends and effectually supporting said plate. As a further means for rendering the purposes of the plate 11 efficient the bolster 80 members 10 may be formed with upwardly-extending lugs 25 to enter corresponding vertical openings 26 in the ends of the top plate 11, whereby said plate and members become shouldered against each other in line with 85 the length of the bolster and resist any longitudinal strains tending to separate them. The plate 11 extends directly across the plate 15 and bridges the space between the inner separated ends of the bolster members 10. 90

The center plate and center-sill filler 12 are in the form of a cast frame (shown in detail in Figs. 8, 9, and 10) and comprising a center-bearing 27, a horizontal plate 28, and vertical transverse plates 29, connected by webs 95 30 and apertured to receive securing-rivets. The plates 29 fit in between and engage the center sills 14, and the plate 28 is in engagement with the lower edges of said sills and at its ends enters recesses 31, formed in the 100 lower inner corners of the bolster members 10, the ends of said plate 28 being secured in said recesses and to said members 10 by means of rivets 32. Between the inner ends of the bolster members 10 and the adjacent vertical 105 walls of the center sills 14 are filling-pieces 13 of usual character. The inner ends of the bolster members 10, fillers 13, sills 14, and plates 29 are secured together by rivets 33. The outer ends of the bolster members 10 are 110 secured by rivets 34 within the side car-sills 16.

In removing the bolster from a car-body

the rivets 24, 32, 33, and 34, securing the parts of the bolster together and to said body, will be cut and removed, and thereupon the center plate and center-sill filler-frame 12 5 may be drawn downwardly, the filling-pieces 13 removed, and the members 10 turned downwardly at their inner ends and withdrawn from the side sills 16, the car-body being left unimpaired. The bolster or a new 10 bolster of like character may be restored or applied to the car-body by returning the members 10 to position, inserting the fillers 13, applying the center plate and center-sill filling-frame 12, and riveting the parts together and to the sills 14 16.

I do not limit the invention to the details of form and construction hereinbefore specifically described, because I am aware that changes may be made in the construction 20 presented without departing from the spirit of my invention.

As an illustration of modifications that may be made in the bolster I refer to Figs. 11, 12, and 13, which illustrate modified forms 25 of the upper tie-plate 11. In Fig. 11 the tie-plate 11 is illustrated as seated against shoulders 35, formed at opposite sides of the bolster member 10. The shoulders 35 resist any tendency of the bolster members 10 to separate under longitudinal strains from the plate 11 and also prevent any swiveling action of the bolster members 10 at their points of connection with said tie-plate 11. In Fig. 12 I illustrate the tie-plate 11 as in the form of a 30 link and engaging upwardly-extending projections 36, formed on the bolster members 10, said projections 36 affording means for shouldering the members 10 against the plate 11 and being a substitute for the shoulders 35. 35 (Illustrated in Fig. 11.) In Fig. 12 I also illustrate the brackets 23 as cast with the bolster member 10 instead of with the tie-plate 11. In Fig. 13 I illustrate a further method of shouldering the tie-plate against the bolster 40 members, the construction shown in Fig. 13 employing the shoulders 35 of Fig. 11, but illustrating the brackets 23 as cast with the bolster member 10 instead of with the plate 11.

What I claim as my invention, and desire 50 to secure by Letters Patent, is—

1. A car-bolster comprising separable main members at opposite sides of the center sills, means above said sills connecting said members, and a plate connecting the inner ends of 55 said members below said sills and at its ends

set into recesses therein; substantially as set forth.

2. A car-bolster comprising separable main members at opposite sides of the center sills, means above said sills connecting said members, a filler-frame between said sills and affording a center-bearing, fillers between the inner ends of said members and said sills, and means securing said frame, sills, fillers and inner ends of said members; substantially as 6 set forth.

3. A car-bolster comprising main members at opposite sides of the center sills, a plate above said sills connecting said members and engaging shoulders thereon, and a 7 connecting-plate below said sills engaging recesses in the inner ends of said members; substantially as set forth.

4. A car-bolster comprising main members at opposite sides of the center sills, a 7 plate above said sills having open portions whose side and outer-end walls engage shoulders on said members, and means spanning the space between said sills and connecting the inner ends of 8 said members; substantially as set forth.

5. A car-bolster comprising main members at opposite sides of the center sills, a plate above said sills having openings therein engaging vertical projections on said members, and means spanning the space between 8 said sills and connecting the inner ends of said members; substantially as set forth.

6. A car-bolster comprising separable main members at opposite sides of the center sills, 9 a plate above said sills connecting the inner ends of said members and having the depending brackets at opposite sides of its ends, and means spanning the space between said sills and connecting the inner ends of 9 said members; substantially as set forth.

7. A car-bolster comprising separable main members at opposite sides of the center sills, means above said sills connecting said members, and means spanning the space between 10 said sills and connecting the inner ends of said members; substantially as set forth.

Signed at New York city, in the county of New York and State of New York, this 4th day of January, A. D. 1906.

JOHN McE. AMES.
